UNITED STATES PATENT OFFICE.

CHARLES J. WATTERS, OF FOX CHASE, PENNSYLVANIA, ASSIGNOR TO NORTH AMERICAN LACE COMPANY, OF PHILADELPHIA, PENNSYLVANIA, A CORPORATION OF PENNSYLVANIA.

DESIGN FOR LACE FABRIC.

43,585.

Specification for Design.

Patented Feb. 18, 1913.

Application filed November 5, 1912. Serial No. 729,652. Term of patent 7 years.

To all whom it may concern:

Be it known that I, CHARLES J. WATTERS, a subject of the King of Great Britain and Ireland, residing at Fox Chase, Montgomery county, State of Pennsylvania, have invented a certain new, original, and ornamental design for Lace Fabrics, of which the following is a specification, reference being had to the accompanying drawing, forming part thereof.

The figure is a plan view of a portion of lace edging, showing my new design.

I claim:

The ornamental design for a lace fabric, as shown.

CHARLES J. WATTERS.
